UNITED STATES PATENT OFFICE.

JOSEPH RITTENHOUSE, OF PHILADELPHIA, PENNSYLVANIA.

DESIGN FOR A NECK-BAND FOR VESSEL-CARRYING DEVICES.

SPECIFICATION forming part of Design No. 32,187, dated February 6, 1900.

Application filed October 25, 1899. Serial No. 784,782. Term of patent 14 years.

To all whom it may concern:

Be it known that I, JOSEPH RITTENHOUSE, of Philadelphia, in the county of Philadelphia and State of Pennsylvania, have invented and produced a new and original Design for a Neck-Band for Vessel-Carrying Devices, of which the following is a full, clear, and exact description.

Reference is to be had to the accompanying drawings, forming part of this specification, in which similar characters of reference indicate corresponding parts in both views.

Figure 1 is a perspective view of a neck-band for vessel-carrying devices embodying the features of my design, and Fig. 2 is a plan view of the same.

My design consists in the features of con-

figuration of the neck-band illustrated in the accompanying drawings, in which the band A is shown as being circular in shape, loops B C 20 appearing at diametrically - opposite points and standing directly out from the circumference of the band and at right angles to the plane of the latter, while at one side of the band, midway between the loops B C, appear 25 hooks D, interlocked and each extending as shown.

I claim—

The design for a neck-band for vessel-carrying devices as herein shown and described. 30
JOSEPH RITTENHOUSE.
